UNITED STATES PATENT OFFICE

1,966,922

GRAVE MARKER

Edward A. Coleman, St. Louis, Mo.

Application May 19, 1933, Serial No. 671,929
Renewed June 12, 1934

1 Claim. (Cl. 40—124.5)

The present invention relates to a grave marker and has for its prime object to provide a device which is simple in its construction, inexpensive to manufacture, attractive and neat in appearance, and thoroughly efficient and reliable in use.

With the above and numerous other objects in view as will appear as the description proceeds, the invention consists in certain novel features 10 of construction, and in the combination and arrangement of parts as will be hereinafter more fully described and claimed.

In the drawings:

Figure 1 is a top plan view of the marker embodying the features of my invention.

Figure 2 is a sectional view taken substantially on the line 2—2 of Figure 1.

Figure 3 is a side elevation of the marker embedded in the ground.

Figure 4 is a similar view showing the marker in a different position.

Figure 5 is a sectional view taken substantially on the line 5—5 of Figure 2; and

Figure 6 is a detail section taken on the line 25 6—6 of Figure 2.

Referring to the drawings in detail it will be seen that the numeral 5 denotes a rectangular base plate from which depends obliquely a spike 6 having the sides thereof grooved out as is indicated at 7 in Figure 6. A sheet of waterproof material 8 is disposed on the base plate. A card 9 is disposed on the sheet 8, a transparent panel 10 is disposed on the card 9 and a washer 11 of rectangular construction is disposed on the panel 35 10 and all of these parts are held assembled by a rectangular frame F. This frame F comprises a body 12 having a marginal depending flange 14 to extend over the edges of the base plate 5, a shoulder 15 to rest on the sheet 8 and a shoulder 40 or overhanging portion 16 to rest on the washer

11. Screws 17 extend through openings in the base plate 5, the sheet 8 and are threadedly embedded in the body 12 to hold the same down tight on the waterproof elastic or compressible sheet 8 and the similarly constructed washer 16 thereby 60 making the marker watertight. The oblique disposition of the spike permits the marker to be used in various ways such as illustrated in Figures 3 and 4 to conform with the lay of the land where the marker is to be placed.

It is thought that the construction, utility and advantages of the invention will now be quite apparent to those skilled in this art without a more detail description thereof.

The present embodiment of the invention has 70 been described in considerable detail since in actual practice it attains the features of advantage enumerated as desirable in the statement of the invention as hereinafter claimed but it is to be understood that changes in the details of construction may be resorted to without departing 75 from the spirit of the invention as claimed.

Having thus described my invention, what I claim as new is:

A grave marker of the class described comprising a base plate, a sheet of waterproof elastic material superimposed on the base plate, a card superimposed upon the sheet, a transparent panel superimposed upon the card, a washer of waterproof and elastic material mounted on the panel, 80 and a frame including a body with a marginal depending flange to extend about the edges of the base plate and having a shoulder to rest on the sheet, and a shoulder to rest on the washer, and elements extending through the base plate and 85 the sheet and embedded in the body of the frame to hold the above enumerated elements assembled.

EDWARD A. COLEMAN.
